UNITED STATES PATENT OFFICE.

JOHN COLEMAN, OF LAKWOOD, OHIO, ASSIGNOR TO THE BABCOCK & WILCOX COMPANY, OF BAYONNE, NEW JERSEY, A CORPORATION OF NEW JERSEY.

LIQUIDS-SEPARATING DEVICE.

Application filed August 10, 1921. Serial No. 491,096.

My present invention relates to devices for the separation of two fluids of different specific gravities, and particularly such a device as may be applied to the separation 5 of oil and water.

One of the objects of my invention is to provide an apparatus of the character described, in which a continuous separation of a mixture of the two fluids may be carried 10 on. Another object of my invention is to provide such an apparatus in which the separation will be carried on positively and with certainty under widely varying conditions.

With these and other objects in view, my invention consists in the arrangements and constructions hereinafter described and more specifically pointed out in the appended 15 claims.

In the drawings, Figure 1 is a vertical section of an illustrative form of apparatus embodying my invention; Fig. 2 is the same as Fig. 1, but showing the operating conditions as they will normally exist; Fig. 3 is 20 an outside view of the upper part of the arrangement shown in Fig. 1; Fig. 4 is a plan of Fig. 3, and Fig. 5 is a section on the line 7—7 of Fig. 1.

In the drawings the same reference characters refer to similar parts in the several views.

In the illustrative arrangement, which is an apparatus adapted to separate oil and water, a tank 10 which is relatively long and of relatively small area is provided with a vertical tube or pipe 11 extending from a point near the bottom of the tank 10 to a point near its top. At the top of the pipe 11 is a chamber 12 having a continuation or 35 air vent 13 running closely to the top of the tank 10.

Projecting from the side wall of the chamber 12 is a water outlet pipe 14, having inside of the chamber an upturned end 40 15 which is flat and at right-angles to the axis of the tank 10. The pipe 14 projects through the walls of the tank 10.

Projecting through the wall of the tank 10 is an oil outlet pipe 16 having its inner 45 end projecting upwardly and terminating in a flat end 17 located at a fixed distance from the end 15 of the pipe 14. Supported above the end 17 is a mushroom 18 extending over the end 17. Through the cover of 50 the tank 10 may be inserted an inlet pipe

19, the cover having a hinged portion 20 with a hole through which the pipe 19 may be inserted. The lower end of the pipe 11 is supported from the bottom of the tank 10 by a member 21.

The operation of my device depends on the fact that by providing the pipe 11, a pair of columns of fluids are provided which tend to become balanced. When the inlet pipe 19 is open and the mixture of oil and water passes into the tank 10, the oil will come to the surface, the pipe 11 containing only water, since it draws from the bottom of the tank 10. As soon as the column of water in the tube 11 reaches the level of the top of the pipe 15, the water will flow out through the pipe 15. If only water passed through the pipe 19, the level outside of the pipe 11 would be the same as that inside and consequently, since the end 17 is higher than the end 15, no fluid would pass through the pipe 16. As the oil gradually accumulates at the top of the tank, the level outside the pipe 11 will be gradually raised until the level of the end 17 is reached, when the oil 70 on top of the water will pass into the pipe 16 and be drawn off. Pipes 14 and 16 are made large enough to carry off the portions of oil and water coming through the pipe 19.

Under normal conditions with, say, oil of 18° Baumé mixed with the water, the operating conditions shown in Fig. 2 will soon become normal and remain so, so long as substantially the same mixtures of oil and water are passing through the inlet 80 pipe 19, with the level of the plane of division between the oil and water at, say, the line A—A of Fig. 2. The lighter the oil, the higher this level will be before the oil begins to flow over the top of the pipe 16, the various levels for the apparatus illustrated being indicated in Fig. 1 at the lines B—B, C—C and D—D. By providing the mushroom 18, the possibility of the mixture of oil and water passing directly into the pipe 16 is prevented, the incoming fluid being caused by this mushroom to spread over the surface of the fluids and the tank 10 to be separated before passing into their respective outlets.

By arranging the inlet pipe 19 above the mushroom 18, the incoming oil and water is broken up into relatively small drops and this facilitates the removal of finely divided particles of oil from the water. The 110

relatively small drops of water carrying these small particles of oil pass down through the mass of oil on the top of the column, thus permitting these small oil particles to be caught and retained by the mass of oil or to be washed out of the water drops, as it were. Moreover, by spacing the end of the inlet pipe 19 a considerable distance above the mushroom 18, this breaking up into 10 drops is facilitated by the splashing which results and the water drops have considerable velocity. Consequently, any small oil particles not removed by passing through the layer of oil are carried down a considerable distance 15 into the water in the tank so that time is given to permit them to separate from the water. These particles, rising through the water tend to sweep out other smaller particles to which they adhere. The 20 total result is a substantially entire separation of the oil from the water. This is particularly important when the device is used to separate oil from boiler feed water, because of the importance of removing all of 25 the oil from the water before sending it into the boiler.

By fixing the relations between the ends 15 and 17, and particularly by having such ends flat and horizontal, I have provided a 30 device in which the operating conditions remain constant under all of the varying conditions which may exist. For instance, if the apparatus be provided for boiler feed water when used in such places as oil tank ships, in which leakage from the oil tanks 35 may pass into the feed water, then under normal conditions there would be little or no oil leaking into the boiler system. Under these conditions, the situation depicted 40 in Fig. 2 will obtain and the respective fluids will flow evenly over the tops of the flat ends 15 and 17, respectively. If through some accident, a sudden increase in the oil coming through the pipe 19 is produced, 45 then there will be a tendency to raise the total levels of the fluids in the tank 10. Since the tops of the pipes 14 and 16 are level, however, the operating conditions will not change because of this, as would be the 50 case, for instance, if the entrances to these pipes were on the side through holes, the active area of which would vary with the rise of the levels of the fluids. This sudden 55 rise of the total levels, however, would force the column of water in the tube 11 somewhat

above the end 15, and then, when the incoming supply through the inlet 19 is shut off, the levels will fall to the positions with the level of the oil at the level of the end 17, but with the water level in the pipe 11 somewhat below the end 15. When a normal incoming flow is again resumed, no water will flow through the pipe 14 until a sufficient amount of oil and water have entered the tank 11 to form a column outside of the pipe 11 to balance the pressure inside that column when its level is at the end 15.

The arrangement shown in the drawings is merely illustrative and may be varied within wide limits. By having the tank 70 relatively long and narrow, I have provided an apparatus in which only a relatively small total quantity of the fluids will be held, but in which the separation may take place readily. By having the tank very 75 long so that the height of the respective fluid columns will be comparatively high, a greater difference between the levels of the ends 15 and 17 will be possible than if such columns were shorter. This difference insures the drawing off of the oil with a minimum disturbance of the plane of separation between the oil and the water. By providing the chamber 12, I am enabled to produce an apparatus in which the top of the 80 water outlet pipe 14 may be flat and upturned.

I claim:—

1. In a separator for removing oil from a mixture of oil and water, a tank arranged 90 to contain water with a layer of oil floating thereon, said tank having a water outlet and an oil outlet above the level of the water outlet, an inlet arranged to deliver the mixture of oil and water above the layer of oil 95 in the tank, and means to break up the entering mixture into relative small drops and to prevent the entry of such drops into the oil outlet.

2. In a separator for removing oil from 100 a mixture of oil and water, a tank arranged to contain water with a layer of oil floating thereon, said tank having a water outlet and an oil outlet above the level of the water outlet, an inlet for a mixture of oil and 105 water above the oil outlet, and a splash plate beneath said inlet and arranged to prevent entry of drops into the oil outlet.

JOHN COLEMAN.
